UNITED STATES PATENT OFFICE.

MILTON E. ANDERSON, OF LOUISVILLE, KENTUCKY.

40001 AVAILABLE COPY

INSULATOR.

992,397.

Specification of Letters Patent. Patented May 16, 1911.

Application filed August 18, 1910. Serial No. 577,748.

To all whom it may concern:

Be it known that I, MILTON E. ANDERSON, a citizen of the United States, residing at Louisville, in the county of Jefferson and State of Kentucky, have invented certain new and useful Improvements in Insulators, of which the following is a specification.

This invention relates to an improvement in insulators, the object being to provide a device of this character which will effectively grip the wire without the necessity of winding or twisting the same.

Another object of the invention is to so construct the device that the same may be readily and conveniently secured to the insulator bracket.

In the drawings: Figure 1 is a view showing the device in position on the bracket. Fig. 2 a sectional view of the device. Fig. 3 a top plan view of one of the insulator sections. Fig. 4 a view showing a slightly modified form of said section, and, Fig. 5 a sectional view of the modification arranged on the insulator bracket.

In the drawings: 10 designates the insulator bracket which is provided with the usual threaded portion 11. Arranged on this member is the glass section 12 of the insulator which is provided with the screw-threaded apertures 13 and 14, the aperture 13 being adapted to receive the screw-threaded portion on the bracket and the aperture 14 being adapted to receive the screw-threaded plug 15. The upper surface of this member is provided with grooves 16 adapted to receive the wire 16', said grooves being so arranged as to allow the wire to be positioned at any angle. The clamped section of the insulator consists of a glass member 17 which is provided with the flared extension 18 and the centrally arranged threaded aperture 19.

It will be seen that when the wire is positioned in one of the grooves 16 the member 17 when screwed down in the position shown in Fig. 2 will securely clamp said wire, the flared extension 18 preventing ice and snow from accumulating between the insulator sections. It will also be noted that the plug

15 which may be formed of wood may be readily removed and replaced by a new one 50 when the same becomes worn.

In the modification shown in Fig. 4 the plug 15 is formed of glass said plug being integral with the section 12.

The many advantages of a device of this 55 character will be clearly apparent as the same will not only be efficient in practice but economical to manufacture. Particular attention is called to the flared extension 18 which is arranged above the contacting surface of the member 17 thus allowing the wire to be readily inserted. 60

What is claimed is:

1. An insulator consisting of a lower section, said section being formed with a plurality of threaded apertures, one of said apertures being adapted to receive the end portion of a supporting bracket, a screw-threaded plug adapted to rest within the other aperture, the upper surface of said section being provided with grooves, an upper section, said upper section being provided with a centrally threaded aperture and an annular flared extension formed integral with said upper section. 75

2. The combination with a supporting bracket having an upper threaded end, of an insulator base having a pair of aligned threaded sockets formed therein and separated by a partition of insulating material, 80 one of said sockets being adapted to engage the threaded end of the bracket, an externally threaded wooden plug engaged in the other socket of the insulator base, and an upper insulator section having a threaded 85 socket formed therein to receive the upper end of the plug to permit the upper section to be screwed down on the plug to clampingly engage the base section of the insulator. 90

In testimony whereof I affix my signature, in the presence of two witnesses.

MILTON E. ANDERSON.

Witnesses:

E. W. ELLIOTT,
J. C. HAWES.
